COMBINED TRAY FOR HOLDING RUBBER STAMPS OR THE LIKE AND SUPPORT THEREFOR

Benjamin B. Cannon, Detroit, Mich., assignor to Burroughs Adding Machine Company, Detroit,
Mich., a corporation of Michigan

Application May 2, 1952, Serial No. 19,568

Term of patent 14 years

(Cl. D74—1)

To all whom it may concern:

Be it known that I, Benjamin B. Cannon, a citizen of the United States, residing at Detroit, county of Wayne, State of Michigan, have invented a new, original, and ornamental Design for a Combined Tray for Holding Rubber Stamps or the like and Support Therefor, of which the following is a specification, reference being had to the accompanying drawing forming a part hereof.

In the drawing:

The figure is a perspective view of the combined tray for holding rubber stamps or the like and support therefore embodying my new design, the opposite side being the same in appearance as the side shown.

I claim:

The ornamental design for a combined tray for holding rubber stamps or the like and support therefor, as shown.

BENJAMIN B. CANNON.
